ADJUSTABLE NOZZLE

Clarence R. Curtis, Lombard, Ill., assignor to F. H. Smith Manufacturing Co., Chicago, Ill., a corporation of Illinois

Application August 7, 1948, Serial No. 43,017

12 Claims. (Cl. 299—73)

1 The present invention relates to an improved fluid nozzle and more particularly to an adjustable nozzle for use as a shower head, fountain spray, fuel nozzle, and other similar applications.

In the art of adjustable nozzles, many types of nozzle constructions have been proposed and employed for specific purposes. However, each of the varied and complicated nozzle structures of the prior art has been limited in its application to a relatively small number of specific uses. The present invention now provides an improved, simple, easily manufactured and inexpensive form of adjustable nozzle, the novel features of which may be employed in nozzles of widely varying construction and use. For example, the present invention is particularly described herein as embodied in a shower head, but it should be appreciated that the same nozzle construction may be employed in a fountain spray or as a fuel nozzle in heat exchange apparatus employing liquid fuel.

It is, therefore, an important object of the present invention to provide an improved nozzle capable of being utilized for a number of different uses, the nozzle being simple and rugged in construction and adapted for inexpensive production.

It is a further object of this invention to provide a nozzle in which a member extending transversely to the flow of water through the nozzle is provided to overlie shoulders extending into the fluid stream, the position of said member relative to said shoulder determining the character of the fluid stream from the nozzle.

It is a yet further object of the present invention to provide an adjustable nozzle of simple and inexpensive construction, the nozzle being capable of completely modifying the character of the stream issuing therefrom upon very limited adjustment of the nozzle.

It is still another object of the present invention to provide an adjustable nozzle in which the character of the stream issuing therefrom may be modified by relative adjustment of a plurality of parts of the nozzle.

Other and further objects of this invention will become apparent from the disclosures in the specification and the accompanying drawings.

On the drawings:

Figure 1 is an elevational view of the nozzle of the present invention;

Figure 2 is an enlarged cross-sectional view of the nozzle of Figure 1 taken on the plane II—II of Figure 1;

Figure 3 is an exploded sectional view illus-

trating the construction and the assembly of the nozzle of the present invention;

Figure 4 is a cross-sectional view taken along the plane IV—IV of Figure 2;

5 Figure 5 is a schematic cross-sectional view of the fluid directing members of the nozzle of Figure 1 showing the members at the "zero position";

10 Figure 6 is a schematic plan view showing the fluid directing members at an "intermediate position";

Figure 7 is a schematic cross-sectional view taken on the plane VII—VII of Figure 6;

15 Figure 8 is a schematic perspective view similar to Figure 6; and

Figure 9 is a schematic plan view showing the fluid directing members at the "right-angle position."

As shown on the drawings:

20 As best shown in Figure 1, the adjustable nozzle of the present invention, indicated generally by the reference numeral 10 and illustrated as employed in a shower head, comprises essentially a pipe fitting 11, a ball member 12, a housing 13, and a nose 14. The fitting 11, the housing 13 and the nose 14 are each provided with knurled portions to facilitate the grasping of these portions of the nozzle by the hand of the operator both during the assembly and the use 30 of the nozzle.

More particularly, the pipe fitting 11 is provided with a central threaded aperture 16 so that the nozzle 10 may be secured to a suitable source of liquid under pressure. The pipe fitting 11 is also provided with a lower central aperture 17 in full communication with the threaded aperture 16.

The ball member 12 is provided with a central upwardly extending portion 18 contoured to 40 provide a shoulder 19, and above the shoulder 19 providing an upstanding cylindrical portion 20 of slightly smaller diameter than the aperture 17 in the pipe fitting 11. Ball member 12 is provided with a centrally extending aperture 21 flared outwardly at its upper end as at 22. As illustrated in Figure 2, the upstanding portion 20 of the ball member 12 is adapted to be received by the aperture 17 of the pipe fitting 11 with the shoulder 19 resting against the lower surface 11a of the pipe fitting. That part of the portion 20 extending into the pipe fitting 11 is pinched outwardly to overhang the aperture 17 retaining the portion 20 in position within the aperture 17 with the ball 12 depending from fitting 11.

45 As shown in Figures 2 and 3, a portion of the

housing 13 is defined by a nut 23 having a hollow central aperture 24. The aperture 24 is constricted at its upper end to define a frusto-conical seating face 26 adapted to be seated on the outer periphery of the ball member 12. As illustrated in Figure 3, the nut 23 is lowered over the ball 12 to bring the face 26 into contact with the outer surface of the ball 12 prior to the assembly of the ball within the pipe fitting. The face 26 is in sliding contact with the outer periphery of the ball 12 to permit swivelling movement of the entire housing 13 so that the stream of liquid passing through the nozzle may be directed as desired. The aperture 24 is internally threaded as at 27 intermediate the extreme ends 15 of the nut 23. Nut 23 carries a depending skirt portion 23a extending beyond the threads 27.

A body portion 28 externally threaded about its upper end as at 29 is adapted to be threaded into the nut 23, the threads 29 engaging the internal threads 27 of the nut 23. The body 28 is centrally apertured to provide internal shoulders 30, 31 and 32, defining stepped apertures 30a, 31a and 32a respectively, as shown in Figure 3. Free passage of liquid through the body portion is provided by the aperture 34 in the lower surface of the body 28 and in communication with the aperture 32a. The shoulder 32 is formed with an annular upstanding ridge 33 surrounding the aperture 34 in the lower extremity of the body member 28. The body 28 is also provided with an external shoulder 36 positioned directly beneath the threads 29.

A washer or sealing ring 37 of rubber or suitable plastic material such as nylon is adapted to be positioned in the aperture 30a of the body portion 28, the washer being in surface contact with the lower portion of the ball 12 when the body member is threaded into the nut 23. An annular ring 38 is adapted to be seated on the shoulder 31 of body member 28 beneath the washer 37, the upper extremity of the ring being in sealing contact with the lower surface of the washer when the nozzle is assembled as shown in Figure 2. The ring 38 is provided with a conical internal face 39 about its lower extremity, the ring having diametrically opposed recesses 40 formed in the face 39 and extending upwardly into the body of the ring.

A sleeve 41 carrying an outwardly extending annular shoulder 42 at its upper edge is adapted to be inserted within the body portion 28. The shoulder 42 is provided with a depending annular ridge 43 corresponding to the ridge 33 of the shoulder 32. A washer 44 is adapted to be received between the shoulders 32 and 42 to insure a liquid-tight seal therebetween. The sleeve 41 is exteriorly threaded as at 46 in a position adjacent its lower extremity. The sleeve 41 is also provided with an aperture 47 in its upper extremity, the aperture 47 sloping downwardly and inwardly as at 48 to define a restricted orifice 49. Orifice 49 is in full communication with a plurality of stepped apertures 50, 51 and 52 formed in the sleeve 41 below the orifice 49. The stepped apertures 50-52 increase in size beyond the orifice, the aperture 52 being larger than the aperture 51 and the aperture 51 being larger than the aperture 50. The sleeve 41 is also provided with opposing upstanding, segmental shoulders 53 formed integrally with the sleeve 41 and defined by removing diametrically opposed portions of the sleeve 41 about the periphery of the aperture 47.

The plate 54 is adapted to be seated on the

shoulders 53 in a position directly overlying the restricted orifice 49. The plate 54 carries integral upstanding projections 55 of suitable size to be readily received by the slots 40 formed in the ring 38. The plate 54, as best illustrated in Figure 4, extends transversely across the aperture 32a formed in the body portion 28 and has a pair of curved segmental sides 54b and 54c having a radius of curvature approximately equal to that of the shoulders 53 and a pair of parallel, oppositely disposed straight sides 54d and 54e. The plate 54 is movable upon the shoulders 53, the movement of the sleeve 41 relative to the slotted ring 38 causing relative movement between the plate 54 and the shoulders 53.

Rotational movement of the ring 38 within the nut 23 is prevented by the snug engagement of the washer 37 against the periphery of ball 12 and of the ring 38 against the lower surface of the washer. The ring 38, bottomed on shoulder 31, is thus held against rotation upon threading the body 28 into the nut 23. By preventing rotation of the ring 38, any movement of the sleeve 41 will cause relative movement between the shoulders 53 and plate 54.

The nose portion 14 of the nozzle assembly is centrally apertured as at 56, the aperture 56 being concentric with and smaller in diameter than the aperture 34 of the body member 28. The aperture 56 is counterbored and internally threaded as at 57 to threadedly receive the threads 46 of the sleeve 41. The nose 14 is threaded on the sleeve 41 until the lower surface 41a of the sleeve abuts shoulder 59 of the nose 14 defined at the bottom of counterbore 51, thus providing a rigid connection of nose member 14 and sleeve 41 for co-rotation. A spring washer 60 is provided between the nose 14 and the under surface of the body member 28 to permit relative rotational movement therebetween and to maintain shoulder seats 33 and 43 in sealing contact with washer 44.

The ease and economy of manufacture of the nozzle of the present invention will be readily apparent from the above description. Substantially all of the major components of the nozzle are adapted for production by the use of standard screw machine techniques and, with the exception of washers or seal rings, may be prepared from easily worked, relatively soft metals, such as brass. The exterior surfaces of the nozzle may preferably be chromium plated to improve the appearance and durability of the finish. The construction makes the rapid and simple assembly of the apparatus possible while the employment of threaded fittings facilitates repair and inspection of the device.

In the operation of the nozzle of the present invention, the pipe fitting 11 is threaded into a source of liquid under pressure, such as a city water line. The liquid under pressure flows from the pipe fitting through the aperture 21 of the ball 12. The liquid flowing through the aperture 21 passes through the central aperture of the ring 38 to impinge directly upon the plane upper surface 54a of the plate 54. Any leakage of liquid upwardly is prevented by the seal ring 37 while any leakage between the flanges 42 and 32 is prevented by the seal ring 44 positioned therebetween. Following the striking of the upper surface 54a, the liquid flows past the plate through the passageway provided by the plate 54 and the shoulders 53 and then through the aperture 47 and the restricted orifice 49. Following the re-

stricted orifice 49, the liquid passes through the stepped apertures or chambers 50-52, inclusive, in the sleeve 41 and through the larger aperture 56 to issue from the nozzle 10.

The characteristics of the liquid stream issuing from the nozzle 10 may be varied by merely changing the setting of the plate 54 with respect to the sleeve 41. The changing of the relative positions of these members may be brought about by the rotation of the sleeve 41 within the housing 13 by turning the nose in either a clockwise or counter-clockwise direction, as by grasping its exterior knurled surface.

In Figures 4 and 5, the plate 54 is illustrated as centered upon the shoulders 53, so that the side surfaces 53a-53d of the shoulders 53 are parallel to the straight, opposing sides 54d and 54e of plate 54. The angle between the side surfaces of the plate and the side surfaces of the shoulders is zero so this position is herein referred to as the "zero position." In this position, the passages 61 provided by the straight parallel sides of the plate in cooperation with the shoulders and the circular wall surfaces of the aperture 32a are open to their fullest extent. The liquid impinging upon the upper surface 54a of the plate 54 is divided into a pair of separate streams which flow over the sides of the plate into the passages 61.

The liquid entering each of the radially opposed passages 61 is directed inwardly toward the axis of the sleeve 43 as shown by the directional arrows in Figures 5. That portion of the stream entering each of the passages 61 will impinge upon the stream entering the opposing passage. The direction of travel of the liquid is substantially axial to the axis of the cylindrical sleeve 41, since substantially all of the forces which might tend to impart rotational movement to the stream will be nullified by the direct impingement of the two streams ahead of the orifice. The stream passing axially through the apertures 50, 51 and 52 will tend to create a small semi-evacuated region around the upper, peripheral section of the chambers 51 and 52 with the result that a portion of the stream will be drawn into the upper portions of these chambers to impinge against the side walls of the chambers.

It will be seen by those skilled in the art that the liquid stream issuing from the nozzle, when the plate 54 and the shoulders 53 are in zero position, will be substantially cylindrical due to the predominantly axial flow of the liquid. This type of cylindrical stream is to be desired for the thorough drenching or wetting of a relatively small cross-sectional area.

As illustrated in Figures 6-8, inclusive, the sleeve 41 may be rotated within the nozzle so that the side surfaces of the shoulders underlie the plate 54 at an angle to the straight parallel sides of the plate. As shown in the drawings, the sides 53a and 53d extend beyond the confines of the plate 54 and when viewed in plan elevation, as in Figure 6, the sides 53a and 53d form an obtuse angle with the straight parallel sides 54d and 54e of the plate 54. These positions are herein referred to as the "intermediate positions."

In any intermediate position, the passageways 61 are somewhat more restricted than in the zero position as illustrated in Figure 4. However, the liquid impinging upon the upper surface 54a of the plate 54 flows over the sides of the plate into the passageways 61 as de-

scribed in connection with the parallel position.

That liquid flowing past the plate in the proximity of the surfaces 53a and 53d will be deflected along these surfaces and will leave the surfaces 5 in a direction substantially parallel to the surfaces to enter the chamber 47 along a path formed substantially as a projection of the surface 53a or 53d. The stream of liquid striking the circular wall of the chamber 47, traveling 10 in a path substantially tangential to the wall of chamber 47, will be deflected into a circular path, the directional movement imparted to the stream by the shoulder surfaces tending to direct the stream in a path about the inner surface of the circular chamber 47. The water thus circulated in a substantially circular path within the chamber 47 forms a vortex upon contact with the generally conical walls 48, the axis of the vortex being identical with the axis of the 20 sleeve 41. That fluid entering the passageways 61 at points spaced from the surfaces 53a and 53d will also be deflected in a path parallel to the surface 53 by the motion of the liquid adjacent the surface. Thus, substantially all of 25 the liquid entering the chamber 47 is deflected into a circular path as shown in Figure 6.

The fluid striking the surfaces 53b and 53c of shoulders 53 will not flow directly into the chamber 47, since these surfaces will act as barriers to the normal flow of fluid into the chamber 47. The flow of the main liquid stream through the passageways 61 will serve to set up eddy currents in the confined fluid as indicated by the directional arrows 62.

30 Both an axial and a radial component of force are imparted to the fluid entering the orifice 49. If a widely divergent spray is desired, the fluid stream may be released from the nozzle immediately following its passage through the orifice 49. However, in most applications, as in a shower head, it is desirable to limit the conical spray angle, as by the conically stepped chamber 50-52. That portion of the stream having the greatest rotational component of velocity is deflected into the main fluid stream by the confining interior walls of the chambers so that the 40 conical configuration of the stream is limited during its passage through that portion of the nozzle lying beyond the orifice.

45 Thus, the cone of dispersion of the conical stream is determined by the size and location of the stepped apertures 50-52 and the liquid issuing from the nozzle 10 continues its conical path due to the rotational force imparted to the liquid during its passage through the nozzle. The liquid is broken up into a finely divided stream by the combination of the swirling motion, their direct impingement upon the surfaces of the chamber 47 and the stepped chambers 50-52. Thus, a fine conical spray may be obtained from the nozzle 10 by relative adjustment of the plate and the sleeve to the intermediate position, and the intensity of the fluid flow is determined by the specific position of the shoulders relative to the plate. This finely divided conical spray is to be greatly desired when evenly distributed fine showers of liquid are desired, as in heat exchange apparatus employing liquid fuel, in a shower head, or in a lawn sprinkling nozzle.

As shown in Figure 9, the sleeve may be rotated relative to the plate 54 to still another position in which the shoulder surfaces 53a-53d are each at right angles to their respective adjacent straight plate sides 54d and 54e. The angle

between the side surfaces of the plate and the shoulder surfaces in this instance is 90° and this position is herein referred to as the "right angle position." In the right angle position, four passages 61 of equal size are provided at spaced points overlying the restricted orifice 49.

The liquid flow entering each of the passages 61 will be deflected inwardly toward the axis of the sleeve as shown by the directional arrows in Figure 9. The stream portions, directed inwardly by the shoulder surfaces 53a-53d, inclusive, will be directed at each other as shown by the arrows and will impinge directly upon each other. Due to the direct impingement of the opposing streams, any rotational movement imparted to any one of the streams will be nullified by the oppositely directed stream impinging directly thereon. Accordingly, a straight flow of liquid through the sleeve will be obtained in the manner described in connection with the zero position, and a relatively straight, generally cylindrical flow stream will be obtained as described above.

It is to be noted that in each position of the plate relative to the sleeve, the characteristics of the stream are determined following the passage of the stream beyond the plate 54. The different characteristics of the stream are obtained by the manner of flow into the chamber 47 as determined by the positioning of the plate relative to the shoulder. Accordingly, the nature of the upper surface 54a of the plate has relatively little effect upon the character of the stream, and the upper plate surface 54a may be of any desired shape.

It is also to be noted that in each of the positions a relatively large passage is provided for the fluid stream throughout all portions of the nozzle. Even in the 90° position, the passages 61 are relatively large while the height of the passage, determined by the height of the shoulders 53, remains constant. This feature of the present invention makes possible the self-cleaning of the nozzle with the elimination of foreign particles which would clog the restricted opening of conventional nozzles.

It should be understood that the design herein presented may be greatly modified without affecting the efficiency or mode of operation of the nozzle.

For those applications where a single stream configuration is desirable, the design of the nozzle specifically described herein may be greatly modified and simplified while retaining the large fluid passages. The desired characteristics of the non-adjustable stream may be selected from the wide variety of stream contours and intensities which may be obtained by changing the relative positions of the plate and sleeve or by changing the number and size of the conically stepped apertures 50-52.

Thus, it will be appreciated that the design of the sleeve 41 and of the plate 54 may be employed in many different types of nozzles with the same beneficial results as obtained in the illustrated embodiment, since the present invention is not limited to the employment of the element in a shower head such as that as has been hereinbefore described. For example, it has been found that this type of construction may be advantageously employed in a nozzle for the introduction of liquid fuel into a furnace or other heat exchange apparatus. Also, by slight modification this construction may be employed in a fountain nozzle or other similar device.

Accordingly, it will, of course, be understood that the various details of construction may be

modified throughout a wide range without departing from the principles of this invention, and it is, therefore, not the purpose to limit the patent granted hereon otherwise than necessitated by the scope of the appended claims.

I claim as my invention:

1. In an adjustable spray nozzle including a ball member secured to a source of fluid under pressure and having a centrally extending aperture for the passage of fluid therethrough, the improvements of an internally threaded nut mounted on said ball for swivelling movement, a hollow body portion having one end threadedly retained in said nut and having an annular inwardly directed shoulder formed at its other end, a cylindrical sleeve having an annular shoulder formed about one end bottomed on said body shoulder and having a centrally located restricted orifice formed internally of said sleeve, said sleeve having a plurality of stepped apertures in communication with said orifice and increasing in diameter downstream of said orifice, a pair of upstanding shoulders on said sleeve upstream of said orifice, an elongated plate seated in flatwise contact with said upstanding shoulders and disposed transversely to the fluid flow through the nozzle, and means for effecting relative rotative movement between said plate and said shoulders.
2. In an adjustable nozzle having a housing adapted for the flow of fluid therethrough, the improvements of a relatively flat elongated plate positioned in said housing and extending transversely across the flow of fluid with its longest dimension lying normal to the path of fluid flow, a sleeve carried by said housing and disposed in the fluid flow downstream of said plate, said sleeve having an aperture directly underlying said plate, a restricted orifice intermediate the confines of said sleeve and stepped apertures of increasing diameter downstream of said orifice, supporting means carried by said sleeve and extending upstream toward said plate into flatwise contact therewith for supporting said plate within said housing and cooperating therewith to define a passage for fluid to said orifice, and means for effecting relative movement between said plate and said supporting means in a plane lying normal to the path of fluid flow.
3. In an adjustable spray nozzle, a housing secured to a source of liquid under pressure and adapted for swivelling movement, a sleeve rotatably retained in said housing, said sleeve having a restricted orifice for the flow of liquid therethrough and a plurality of stepped apertures of increasing diameter downstream of said orifice, a pair of opposed shoulders on said sleeve ahead of said orifice, and an elongated plate seated flatwise on said shoulders with its longest dimension lying substantially normal to the path of liquid flow through said housing, said sleeve being rotatable to move said shoulders into and out of alignment with the longest dimension of said plate.
4. In an adjustable spray nozzle, a housing secured to a source of liquid under pressure and adapted for the flow of fluid axially therethrough, a baffle plate positioned in said housing and having an upper baffle surface extending radially of the housing in a plane substantially normal to the flow of fluid, means positioned in said housing defining a restricted orifice directly downstream of said plate, a pair of spaced separate supporting means carried by said housing interposed between said plate and said orifice to support said plate and cooperating with said plate to define a re-

stricted passageway for fluid beneath said plate and between said supporting means to said orifice, and means for effecting relative rotational movement between said plate and said supporting means into and out of alignment to vary the path followed by the fluid stream introduced into said orifice.

5. In an adjustable nozzle, means for controlling the flow of fluid through the axial bore of an elongated housing comprising a baffle member positioned within the bore and extending radially thereacross in a plane normal to the flow of fluid through the housing, a second member disposed in said housing bore providing an arcuate rotatable mounting shoulder for supporting said first member and cooperating therewith to define a passageway directly downstream of said baffle member, and means secured to said second member and extending exteriorly of said housing for effecting rotation of said second member relative to said baffle member.

6. An adjustable spray nozzle comprising a housing having an axial bore for the flow of fluid therethrough, a generally flat plate positioned in said housing and having its two longest dimensions extending radially across the bore of said housing and a sleeve rotatably disposed in said housing downstream of said plate, said sleeve having a pair of upstanding arcuate shoulders abutting the under surface of said plate and a central restricted orifice directly downstream said plate, said plate and said shoulders cooperating to define a passage for fluid beneath said plate to said orifice and being capable of relative rotational movement about the axis of the bore of said housing to vary the path of fluid flow to said orifice.

7. An adjustable spray nozzle comprising a housing having an internal bore adapted for the flow of fluid therethrough, an annular ring seated in said nozzle and having a central bore aligned with that of said housing, said ring being fixed against relative movement in said housing and having opposed slots formed in its lower annular face, a sleeve rotatably supported within said housing and defining a restricted orifice aligned with said bore for fluid flow through said housing downstream of said ring, said sleeve having a pair of upstanding shoulders extending toward said ring upstream of said orifice, an elongated plate seated on said shoulders with its under surface in flatwise contact therewith and having its longest dimension extending radially across the housing bore in a plane normal to the path of fluid flow therethrough, said plate cooperating with said shoulders to define a passage for fluid between said shoulders downstream of said plate and upstream of said orifice and having projections formed in the upper face for insertion into the slots in said ring to prevent rotation of said plate within the housing, and means for effecting rotation of said sleeve relative to said plate.

8. In an adjustable spray nozzle including a ball member secured to a source of fluid under pressure and having a centrally extending aperture for the passage of fluid therethrough, the improvements of an internally threaded nut mounted on said ball for swivelling movement, a hollow body portion having one end threadedly retained in said nut and having stepped internal shoulders formed therein, a seal ring mounted on one of said shoulders in sealing contact with said ball, an annular ring mounted on a second of said shoulders in sealing contact with said seal

ring and having slots formed in its lower end face, a cylindrical sleeve having an annular shoulder formed about one end bottomed on a third one of said body shoulders and having a centrally located restricted orifice formed internally of said sleeve, said sleeve having a plurality of stepped apertures in communication with said orifice and increasing in diameter downstream of said orifice, a pair of upstanding shoulders on said sleeve upstream of said orifice, an elongated plate seated on said upstanding shoulders and having its two greatest dimensions extending normally to the path of fluid flow through the nozzle, said plate having upstanding projections inserted into the slots formed in said annular ring, and means extending exteriorly of said body portion and engaging said sleeve for effecting relative rotation between said plate and said shoulders.

9. In an adjustable nozzle, means for controlling the flow of fluid through an apertured housing comprising an elongated baffle member positioned in the housing and having its greatest dimension extending in a plane normal to the direction of fluid flow through the housing and flow controlling means in said housing providing a pair of separate arcuate supporting shoulders engaging said baffle member and being rotatable relative thereto, said arcuate supporting shoulders having plane flow directing side surfaces downstream of said baffle member, said baffle member having opposed recessed sides serving to divide fluid flow through the housing into a plurality of separate streams and the flow directing surfaces of said shoulders cooperating with said member to direct said streams through said housing in a spiral path determined by the relative positions of said member and said surfaces.

10. In a nozzle, means for controlling the flow of liquid through the bore of a housing having a discharge outlet comprising a baffle member positioned in the housing and having its greatest dimension extending normal to the flow of fluid through the housing upstream of said outlet, and flow controlling means in said housing providing a pair of projecting shoulders extending along the path of liquid flow therethrough and abutting said baffle member, said baffle member and said shoulders being relatively rotatable about the axis of said bore and said shoulders having flow directing side surfaces extending downstream from said baffle member, said baffle member serving to divide fluid flow through the housing into a plurality of separate streams and the side surfaces of said shoulders cooperating with said baffle member to direct said streams through said housing in a spiral direction determined by the relative angular position of said baffle member and said shoulders.

11. In an adjustable spray nozzle provided with an axial bore adapted for the flow of fluid therethrough, the improvement of a baffle disc extending radially across said bore, said disc having flat faces and arcuate portions removed from opposing curved edges thereof, an axially bored sleeve carried by said housing downstream of said disc and having a pair of arcuate upstanding shoulders engaging said disc and defining plane flow-directing side surfaces directly downstream of said disc, and means for effecting relative movement between said disc and said sleeve to change the path of fluid flow about

said disc between said shoulders, against the shoulder side surfaces and through the bore of said sleeve.

12. In an adjustable spray nozzle having an axially bored housing adapted to the flow of fluid therethrough, the improvement of a disc having flat faces extending in a plane lying normal to the path of fluid flow through said housing and having arcuate portions removed from opposing curved edges thereof, a sleeve rotatably mounted in said housing downstream of said disc, said sleeve having a pair of arcuate shoulders projecting from the sleeve thereof for abutment against one face of said disc and having a reduced orifice downstream of said disc, and means for rotating said sleeve relative to said disc to bring said shoulders into and out of registry with those portions of said disc from which the arcs

have been removed to change the path of fluid flow about said disc to said orifice.
